UNITED STATES PATENT OFFICE.

BERNHARD BARON, OF LONDON, AND GEORGE FREDERICK BULL, OF BIRMINGHAM, ENGLAND.

BOX OR CONTAINER FOR TOBACCO CARTRIDGES.

Application filed April 12, 1922. Serial No. 551,985.

To all whom it may concern:

Be it known that we, BERNHARD BARON, a subject of the King of Great Britain, residing in London, England, and GEORGE FREDERICK BULL, a subject of the King of Great Britain, residing in Birmingham, England, have invented certain new and useful Improvements in and relating to Boxes or Containers for Tobacco Cartridges, of which the following is a specification.

This invention relates to boxes or containers for tobacco cartridges and it has for its object certain improvements in boxes or cases which whilst serving as containers for the said cartridges have combined with them means for thrusting the cartridge into the pipe.

Hitherto such cases have had the pipe charging means arranged at one end and externally thereof whereby when in use an unbalanced effect has been produced under which there was a tendency to unduly incline the device with respect to the axis of the bowl of the pipe whereby the bowl was either imperfectly charged or a certain amount of tobacco escaped without passing into the bowl. Moreover, with the known arrangements, the cartridge was contained in a closed or substantially closed tubular body.

The present invention has for its object certain improvements designed to secure a more compact box or case of this type in which, moreover, it is possible to secure a better balance when in use whereby a more efficient charging of the pipe may be secured. The invention further provides certain improvements in the charging means whereby the placing of the cartridges in position for charging and the removal of the outer wrapper after the charging has been effected can be readily and conveniently effected.

The invention has for its further object certain improvements in the means whereby the tobacco is removed from the paper during the filling operation.

According to this invention a case is provided having a suitable lid or cover. The

charging device is disposed within the body of the case, running transversely of the length or width of said case and preferably disposed in the centre of the length or width thereof as the case may be. A plunger of more or less common form is employed working in a spring or other tubular guide and accessible from the outside of the case. The guide just referred to forms part of or is attached to a body of substantially U shaped cross-sectional outline open upon one side and of such dimensions as to contain the cartridge. The body just referred to terminates in a tapered tubular extension through which the tobacco passes to the pipe. Openings are formed in the box and lid to permit the passage of the tobacco to the pipe bowl. The head of the filler plunger may also be arranged to form a locking means for said case or box.

In order to remove the tobacco from the paper a roughened surface is provided in the form of small inwardly directed perforations forming surfaces or points which pierce the paper and hold it back whilst the tobacco is thrust therefrom.

In order that the invention may be the better understood drawings are appended in which:

Fig. 1 is an elevation of the container when closed,

Fig. 2 is a view with the case open and a cartridge in position ready for charging the pipe,

Fig. 3 is a side view of the charging device removed from the case,

Fig. 4 is a front view of the charging device showing certain modifications,

Fig. 5 is a similar view to Fig. 1 showing further modifications,

Fig. 6 is a side view of the case closed and with the plunger drawn out ready for the filling operation,

Fig. 7 is a sectional view to a larger scale showing the arrangement for locking the case.

Referring to the accompanying drawings a indicates the body of the case and a¹ indi-

cates the cover or lid of the case. Preferably inwardly curved extensions such as *c* are provided upon three sides of the box as shown serving not only to assist in retaining the cartridges when the case is opened but also as guards whereby, when the case is closed, any damage to the said cartridges from the lid is avoided.

Disposed transversely of and in the centre 10 of the length of the case is a filling device the upper and lower ends of which are secured in any suitable manner to the sides of the body of the case. The filling device comprises a plunger *d* of more or less common form adapted to slide in a guide *e* formed at one end of the body *f* which is of substantially U shaped cross-sectional outline open at the point *f*¹, and of such dimensions as to contain the cartridge. Preferably the sides of the open portion *f*¹ are provided with outwardly turned lips or flanges *f*² designed to facilitate the insertion of the cartridge and to prevent injury to the paper wrapper when inserting same.

25 The mouthpiece of the filler is formed by the flanges *w* formed upon the sides of the case.

The height of the sides of the open portion is such that the lips or flanges *f*², when 20 the lid is closed, contact with or are closely contiguous to the inner surface of the said lid which thus forms a closure for the said open portion.

In order to retain the paper wrapper there 35 is secured within the open portion *f*¹ and at the back thereof a thin metal plate *g* indented or perforated from the outside thereby forming a number of sharp points or surfaces which, when the cartridge is placed 40 in position, pierce the paper and hold it back against the thrust of the plunger *d*.

Instead of employing a separate strip such as that *g* just referred to, the indentations may be formed upon the body *f*.

45 Preferably the openings or recesses in the body of the box or case and the lid at the point where the tobacco is discharged into the pipe are provided with projections as shown adapted to fit freely within the mouth 50 of the bowl of the pipe.

Instead of, or in addition to, the points provided to retain the paper wrapper the end of the discharge for the said tobacco may be provided with inturned projections 55 designed to engage the paper wrapper and hold it back. If desired the points or projections, such as those before referred to, may be provided at or near the discharge aperture for the tobacco. Thus instead of 60 being arranged as shown in Figs. 1 to 3 the plate *g* may be omitted and the points for engaging the tobacco may, as just above stated, be formed directly upon the metal of the filler, also, if desired, the trough 65 shaped cross-sectional outline may be con-

tinued to the lower end of the body *f* as shown in Fig. 4.

In use the plunger is drawn out to its fullest extent, a cartridge is then placed in position for said plunger to act thereon. 70 The box, closed, and grasped by three fingers and the thumb, is placed in position over the pipe, the fourth finger being utilized to depress the plunger.

In the case as illustrated in Fig. 5 the lips or flanges *f*² are carried to the lower end of the filler and spring pressed plates *h* are provided to assist in retaining the cartridges when the case is open. In order that the case may be locked there is provided upon the underside of the head of the plunger, an annular space or opening *h*¹ which, when the plunger is depressed, engages the projections *i* formed upon the top of the sides of the case thereby holding said sides together and preventing the opening of the lid unless the plunger is partly or wholly withdrawn.

Obviously instead of being arranged in the centre of the length or breadth of the case the filler may be arranged at any other point providing it is contained within said case. The placing of the filler centrally, however, provides for a better balance when in use.

Claims:

1. A case for tobacco cartridges and comprising body members, a pipe filler in said case having an opening for the introduction of cartridges, a closure for said opening formed by one of the body members, means for facilitating the introduction of a cartridge into said opening and for preventing injury to the wrapper of the cartridge during introduction, and a mouthpiece for the filler.

2. A tobacco case for cartridges and comprising body members, a pipe filler in said case having an opening for the introduction of cartridges, a closure for said opening formed by one of the body members, means for facilitating the introduction of a cartridge into said opening and for preventing injury to the wrapper of the cartridge during introduction, and a mouthpiece for the filler formed upon the sides of the case.

3. A tobacco case for cartridges and comprising body members, a pipe filler in said case having an opening for the introduction of cartridges, a closure for said opening formed by one of the body members, means arranged adjacent to said opening for facilitating the introduction of a cartridge therein and for preventing injury to the wrapper of the cartridge during introduction, and a mouthpiece for the filler formed upon the sides of the case.

4. A case for tobacco cartridges and comprising body members, a pipe filler contained in the case and disposed centrally of the length of said case, said filler having an

5 opening for the introduction of the cartridges, a closure for said opening formed by one of the members of the body of the case, outwardly turned lips at the sides of said opening, and a mouthpiece for the filler formed upon the sides of the case.

10 5. A case for tobacco cartridges comprising a body member, a lid member hinged thereto, a pipe filler contained therein and disposed centrally of the length of the said case, said filler having an opening for the introduction of the cartridges, a closure for said opening formed by one of the members of the body of the case, outwardly turned 70 lips at the sides of the said opening, a mouthpiece for the filler formed upon the sides of the case, a roughened surface within said filler comprising a number of points, a plunger for removing the tobacco from the cartridge and forcing it into the pipe, a tubular guide for said plunger, a head upon said plunger, and means upon the parts of the case engaging 75 other means upon said head when the case is closed and the plunger is in inward position whereby said parts of said case are held in the closed position.

15 6. A case for tobacco cartridges comprising a body member, a lid member hinged thereto, a pipe filler contained therein and disposed centrally of the length of the said case, said filler having an opening for the introduction of the cartridges, a closure for said opening formed by one of the members of the body of the case, outwardly turned 80 lips at the sides of said opening, a mouthpiece for the filler formed upon the sides of the case, a plunger for removing the tobacco from the cartridge and forcing it into the pipe, a tubular guide for said plunger, a head upon said plunger, means upon the parts of the case engaging other means upon said head when the case is closed and the plunger is in 85 inward position whereby said parts of said case are held in the closed position.

20 7. A case for tobacco cartridges comprising a body member, a lid hinged thereto, a pipe filler contained therein and so disposed therein as to provide cartridge containing spaces on each side of said filler, said filler having an opening for the introduction of the cartridges, a closure for said opening formed by one of the members of the body of the case, outwardly turned 90 lips at the sides of said opening, a mouthpiece for the filler formed upon the sides of the case, a plunger for removing the tobacco from the cartridge and forcing it into the pipe, a tubular guide for said plunger, a head upon said plunger, said head having a recess upon the underside 95 thereof, projections upon the lid and body of said case adapted to be engaged by the recess in the head of the plunger and hold the parts in the closed position.

25 8. A case for tobacco cartridges, a pipe filler contained therein and disposed centrally of the length of the said case, said filler having an opening for the introduction of the cartridges, a closure for said opening 100 formed by one of the members of the body of the case, outwardly turned lips at the sides of said opening, a mouthpiece for the filler formed upon the sides of the case, a roughened surface within said filler comprising a number of points, a plunger for removing the tobacco from the cartridge and forcing it into the pipe, a tubular guide for said plunger, a head upon said plunger, and means upon the parts of the case engaging 105 other means upon said head when the case is closed and the plunger is in inward position whereby said parts of said case are held in the closed position.

30 9. A case for tobacco cartridges comprising a body member, a lid hinged thereto, a pipe filler contained therein and so disposed therein as to provide cartridge containing spaces on each side of said filler, said filler having an opening for the introduction of the cartridges, a closure for said opening formed by one of the members of the body of the case, outwardly turned 110 lips at the sides of said opening, a mouthpiece for the filler formed upon the sides of the case, a plunger for removing the tobacco from the cartridge and forcing it into the pipe, a tubular guide for said plunger, a head upon said plunger, said head having a recess upon the underside 115 thereof, projections upon the lid and body of said case adapted to be engaged by the recess in the head of the plunger and hold the parts in the closed position.

35 10. A case for tobacco cartridges, a pipe filler contained therein and disposed centrally of the length of the said case, said filler having an opening for the introduction of the cartridges, a closure for said opening formed by one of the members of the body of the case, outwardly turned lips at the sides of said opening, a mouthpiece for the filler formed upon the sides of the case, a plunger for removing the tobacco from the cartridge and forcing it into the pipe, a tubular guide for said plunger, a head upon said plunger, said head having a recess upon the underside thereof, and projections upon the lid and body of said case adapted to be 120 engaged by the recess in the head of the plunger and hold the parts in the closed position.

40 11. A case for tobacco cartridges and pipe filler comprising a back member, a front member, hinges connecting said back and front members, a pipe filler disposed within and centrally of the length of one member of said case, a tubular portion at the upper end of said filler, a tubular portion at the lower end of said member, an open portion 125 130

between said tubular portions for the introduction of the cartridge, a closure for said open portion formed by one of the members of the case, outwardly turned projections at 5 the sides of said opening, a roughened surface within the open portion, a plunger sliding within the upper tubular portion, a head upon said plunger, said head having a recess in the underside thereof, projections upon 10 the members of the case designed to engage said recess, and a mouthpiece for the filler formed upon the sides of the case.

In testimony whereof we have hereunto

set our hands in the presence of two witnesses.
